UNITED STATES PATENT OFFICE.

EDWARD H. MCLOUD, OF COLUMBUS, OHIO, ASSIGNOR, BY MESNE ASSIGNMENTS, TO THE KINNEAR MANUFACTURING COMPANY, OF COLUMBUS, OHIO, A CORPORATION OF OHIO.

METALLIC DOOR.

1,385,694.

Specification of Letters Patent. Patented July 26, 1921.

Application filed July 31, 1918. Serial No. 247,553.

To all whom it may concern:

Be it known that I, EDWARD H. MCLOUD, a citizen of the United States, residing at Columbus, in the county of Franklin and 5 State of Ohio, have invented a certain new and useful Improvement in Metallic Doors, of which the following is a specification.

The object of this invention is to provide a door or door member of simple and economical form, light in weight and durable 10 in use.

The invention is embodied in the example herein shown and described, the features of novelty being finally claimed.

15 In the accompanying drawings—

Figure 1 is a plan view of the inner side of the door or door member.

Fig. 2 is a vertical section on the line II—II Fig. 1 looking to the left.

20 Fig. 3 is a horizontal section on the line III—III Fig. 1 looking up.

Fig. 4 is a plan view of a blank for the construction of one of the door elements.

Fig. 5 is a perspective view showing one 25 of such door elements formed from such a blank as depicted in Fig. 4.

The blank or piece shown in Fig. 4 is of sheet metal of square or rectangular form with its four corners cut out as shown at 6

30 so that the piece can have its flanges or margins 7 all bent up in the same direction and upon the broken lines to form a cell or pan-like body as indicated in Fig. 5. After the margins are bent up as shown the end of 35 the margins where they meet at the corners are welded or soldered together to complete the cell or pan-like structure, as shown at 8.

If the door is to be used for fire protection the aforesaid margins are preferably welded 40 together. In constructing the door or door member any suitable number of these cells or pan-like bodies are placed margin to margin in one or more rows and riveted together by rivets as illustrated at 9 in Figs.

45 1, 2 and 3.

When two or more rows of the cells united by the rivets 9 are to be employed I interpose between the rows a stiffening bar 10 of greater depth than the margins of the cells 50 and rivet the cells to said bar. The said intermediate bar 10 may also be further stiffened by riveting to it an angle bar 11 along the part that projects beyond the margins.

55 The outer or horizontal edges of the door

or door member can be stiffened by riveting thereto angle bars 12, said last named bars being preferably of the same depth as the intermediate bars 10.

The vertical edges of the door or door member are shown to have riveted to them angle bars 13 projecting from the opposite or outer face of the door or door member and each of these has one of its webs standing inward over the face of the door as best 60 seen in Fig. 3, said bars 13 thus serving not only to strengthen those edges but also to provide channels or guides to receive and retain another sliding door member if desired. 70

The numerous webs formed by the cell margins afford great strength against flexing the door without adding unduly to the weight thereof and the outer side of the door presents a neat, smooth and almost unbroken 75 appearance.

In the drawings I have illustrated a rather small door or door member but the cells or rows of cells may be multiplied indefinitely according to the size required. I herein 80 speak of a door or door member as indicating that the door may be composed of a single structure like that shown or it may be composed of several of them. In the latter case the door members are also denominated 85 as door sections.

The number, forms and proportions of the parts can be changed or some parts omitted without departing from the gist of the invention as claimed. 90

What I claim is—

1. A door section comprising, in combination, a plurality of rows of flanged pan-like cells, a reinforcing bar located between and secured to the flanges of the cells, reinforcing bars secured to the outer flanges of the rows of cells, said reinforcing bars being of greater depth than the flanges of the cells. 95

2. A sliding door section comprising, in combination, a plurality of horizontal rows of flanged pan-like cells, a reinforcing bar located between and secured to the flanges of the cells, reinforcing bars secured along the outer horizontal flanges of the section 105 and reinforcing and guiding bars secured on the vertical flanges, said last named bars projecting in a direction opposed to the direction of the projection of the flanges.

EDWARD H. MCLOUD.
